UNITED STATES PATENT OFFICE.

LESTER A. WERNERY, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,284,004.

Specification of Letters Patent. Patented Nov. 5, 1918.

Application filed April 7, 1917. Serial No. 160,348.

To all whom it may concern:

Be it known that I, LESTER A. WERNERY, a citizen of the United States, residing in Brooklyn borough, in the county of Kings, city and State of New York, have invented certain new and useful Improvements in Type-Writing Machines, of which the following is a specification.

This invention relates to an improvement 10 in typewriting machines, and more particularly to attachments for aiding in the assembling or collating of several sheets, such as ledger sheet, record sheet and statement. This invention is an improvement on my application No. 140,512, filed January 4, 1917.

In my application above-mentioned, I show how three or more sheets of different character, with the writing to be placed upon different lines, might be collated or assembled rapidly in a pack, so that all of them might be simultaneously written on at different distances from the top margins of each sheet. This was done by providing one or two pins to engage notches arranged at 20 different distances from the top leading edges of several different types of work-sheets. The pins were assisted in locating or collating the sheets by guides coöperating with the platen apron and a special guiding table provided at the front of the platen.

In the present improvement, the guiding fingers which are provided on the guiding table are arranged to be adjusted relatively to each other, so as to increase or decrease 25 a space between them to accommodate sheets of different width. Likewise the pins which engage the notches or shoulders provided on the work-sheets are adjustable with the fingers, so as to coöperate with several types of sheets having different widths. In this way the device is made more flexible than before, in that it can accommodate different types of work. This is done by forming the guiding table in two collapsing and 40 expanding sections, each of which carries one of the guiding fingers and one of the stop pins so that the pins and fingers may be spread varying distances apart to accommodate work-sheets of different widths.

50 Other features and advantages will hereinafter appear.

In the accompanying drawings,

Figure 1 is a perspective view of the typewriter carriage, showing the platen and other

mechanism for guiding and collating a plurality of work-sheets of different character. 55

Fig. 2 is a detail view of one end of the guiding table showing how the two halves of the guiding table are adjustably mounted so as to collapse or extend the same. This 60 view also shows the form of the key slot in the rock shaft, permitting the adjustment of the limiting pins which engage the notches on the work-sheets.

Fig. 3 is a fragmentary view of an end 65 elevation, partly broken away, to show the underlying structure, and illustrating the position of the parts when the rock shaft and the stop pins are rotated to their effective position. 70

Fig. 4 is a detail view, showing the rock shaft and the stop pins carried thereby raised to an ineffective position clear of the work-sheets.

Fig. 5 is a detail section, taken through 75 the rock shaft and the guiding table, showing the manner of adjustment of one of the stop pins.

Fig. 6 is a diagrammatic perspective view, 80 showing three sheets of different types with the interleaved carbon sheets in their relatively adjusted positions as determined by the stop pins.

The usual Underwood typewriter carriage includes a frame 1, in which is revolvably 85 mounted a platen 2, which is provided with knobs 3, by which it may be turned, and also with the usual line-space mechanism including the line-space wheel 4, which is adapted to turn the platen in line-space units 90 in the usual manner. To insert a work-sheet in the platen, the work-sheet is passed over a paper table 7, at the rear of the platen, which curves beneath the platen so as to guide the work-sheet out in front of the 95 platen, carrying it past the front and rear feed rolls 8 and 9. These feed rolls normally bear against the platen in order to cause the platen by its revolution to carry the work-sheets forward as it turns, by holding said work-sheets against the platen. The carriage is provided with the usual feed-roll release handle 10, which when depressed to the position seen in Fig. 3, removes the feed rolls 8 and 9 from the platen, thus allowing 100 free passage for the work-sheets. Each of the work-sheets is provided with a shoulder 11 which is adapted to strike and be arrested

2
by a left-hand pin 12, said pin being mounted in a transversely-extending rock shaft 13, which extends across the carriage above the platen and is journaled in brackets 14 fast to 5 the platen frame. There is usually also provided a second right-hand pin 15 which is similarly mounted in the rock shaft 13. A hand-lever 5 secured to the right-hand end of the rock shaft 13 when operated 10 engages and operates the handle 10, so as to cast off the feed rolls 8 and 9 in the usual manner. The depression of the hand-lever 5 also rocks the shaft 13 to bring the pins 12 and 15 forwardly, so that they stand 15 out nearly horizontal (Fig. 3) from the face of a paper-guide table 16, said table extending down some distance toward the printing line and practically into contact with the platen. A detent 6 engages alternatively in 20 a pair of notches provided on the hand-lever 5 to lock the same in either its depressed or raised position.

A work-sheet may then be inserted over the usual paper-table 7, and between the 25 usual side guides 17 and 18, which serve to start it correctly, and then the work-sheet passes up past the rolls 8 and 9, in front of the platen, onto the paper-guide 16. The paper-guide table 16 is formed 30 with guiding fingers 19 and 20, one on each side, so as to properly guide the work-sheets by engagement with the side margin thereof; this coöperates with the usual paper-apron 21 forming an extension of the paper- 35 table 7.

In order to accommodate the work-sheets of different widths, the guide-table 16 is formed in two parts 22 and 23, which overlap each other, so as to be extensible or collapsible, thus varying the distances between the guide-fingers 19 and 20. An adjustment is provided by having a screw or lock 24 on one of the parts engaging in a slot 25 on the other of the parts. The guide table 16 45 is supported indirectly by the rock shaft 13 by having its upper end coiled at 26 around the rock shaft. Interposed between this coiled portion and the rock shaft, there is provided a tubular sleeve 27 secured at each 50 end to the brackets 14. The fingers 19 and 20 are provided with collars 28, which form parts of the coils 26 and are integral with the sections 22 and 23 of the guide table 16. To secure the sections of the guide 55 table 16 in their relative adjusted positions and also secure the guide fingers 19 and 20, they are provided with thumb screws 29, which engage the collars 28, and are tightened up to lock the guiding parts onto the 60 sleeve 27. The pins 12 and 15 are adjusted with the sections of the guide table 16, so as to coöperate with the notches 11 on work-sheets of varying widths. Through this, the pins extend into arcuate slots 30, provided in the coiled portions 26 of the guide

table 16, so that when the table is adjusted, the pins will be adjusted also. The pins 12 and 15 are made adjustable by engaging in T-slots 31, provided in the rock shaft 13. The pins being T-shaped are provided with 70 heads for this purpose. To accommodate the longitudinal and arcuate movements of pins 12 and 15, the sleeve 27 has a longitudinal strip cut out, so as to form a groove or opening 32 the length of the sleeve 27 75 and of sufficient arcuate magnitude to permit the rotation of the pins from the ineffective position shown in full lines, Fig. 5, to the effective position shown in dotted-lines in the same figure. 80

In inserting the work-sheets for book-keeping, there is inserted usually at the bottom a ledger sheet, then a carbon sheet, then, in many kinds of business, some sheet for keeping a duplicate record, and on top of 85 this is inserted a statement sheet. These sheets are usually assembled with interleaved carbon sheets and put into the machine together. In the process of being inserted, the average operative is likely to 90 cause them to slide over to some extent. According to the present invention, each of these sheets is provided with a shoulder which is adapted to bring the right line to the printing point when that shoulder 95 strikes the pin or pins 12 and 15 which are in effective position. Since each statement sheet is usually put into the machine only once, it may be provided with a single permanent shoulder 11 for coöperation with the 100 pin 12, its alinement being secured by placing its edge against one or both side guides 17 and 18. If desirable, the sheet may be provided with two shoulders for coöperation with each of the pins 12 and 15. The 105 shoulder 11 may be on a detachable margin 33 separable from the main sheet or the statement by ripping it along a perforation 34. If desirable, there may be such a perforation or shoulder on each side of the state- 110 ment sheet.

The ledger sheet is provided with a series of detachable shoulders, each separable by a line of vertical perforations and of horizontal perforations from the ledger sheet, 115 as in my prior application, above mentioned. If only one set of shoulders is used on the ledger sheet and the ledger sheet is bound by a post which passes through circular openings 35 in the ledger sheet at the 120 side thereof, then the shoulders are advantageously located on the side of the sheet which lies within the binding of the covers, thus presenting a smooth edge of the sheet in handling the book. 125

When assembled (Fig. 6), the statement 36 is shown in front, next to this and behind it is a carbon sheet 37, behind that the duplicate sheet 38, behind that the second carbon 39 and behind that the ledger sheet 40. 130

The shoulders on the sheets 36, 38 and 40 engage the pins 12 and 15 so as to accurately determine the relative positions of the sheets.

5 Variations may be resorted to within the scope of the invention, and portions of the improvements may be used without others.

Having thus described my invention, I claim:

10 1. The combination with a platen for holding a plurality of work-sheets in a pack, said work-sheets having notches therein located at various distances from the top margin, of a plurality of variably settable spaced stops to admit the body of the work-sheets between them while engaging said notches, so as to collate the sheets on said platen.

20 2. The combination with a platen, of a stop arranged to be at the side of work-sheets intermediate the ends thereof when the work-sheets are in printing position, to engage notches in a plurality of such work-sheets on said platen, so as to collate said work-sheets, and means for shifting said stop into and out of engagement with said notches, said stop having a pin-and-slot connection with said shifting means, so as to be adjustable lengthwise of said platen.

30 3. The combination with a platen, of a plurality of stops for engaging notches in a plurality of work-sheets lying on said platen between said stops, so as to collate said work-sheets, a rock shaft for shifting said stops into and out of active positions, said stops and said rock shaft having a pin-and-slot connection, so as to permit said stops to be adjustable relatively to each other to accommodate work-sheets of different widths, and means for rocking said shaft.

40 4. The combination with a platen, of a rock shaft above said platen, a sleeve for said shaft, a guide table supported by said sleeve in front of said platen, said guide table comprising two sections adjustable along said shaft, so as to accommodate work-sheets of different widths on said platen, and a paper stop on said shaft to rock therewith between effective and ineffective positions.

50 5. The combination with a platen, of a pin to engage notches in a plurality of work-sheets on said platen, so as to collate said work-sheets, a rock shaft for moving said pin into and out of operative position, said pin being adjustable along said shaft, and a sleeve on said shaft for limiting the extent of the rocking movement of said pin, having a longitudinal opening permitting longitudinal movement of said pin along said shaft.

6. The combination with a platen, of a guiding table coöperating with said platen behind the work-sheets to properly position the work-sheets on said platen, said guiding table comprising two sections adjustable relatively to each other to vary the width thereof, so as to accommodate work-sheets of different widths, and a pin carried by each of said sections adjustable therewith and capable of engaging notches on said work-sheets to collate said work-sheets relatively to each other.

7. The combination with a platen, of a guiding table coöperating with said platen to properly position work-sheets on said platen, said guiding table comprising a pair of sections adjustable relatively to each other to accommodate work-sheets of different widths, a pin carried by each of said sections for engaging notches in said work-sheets to collate them relatively to each other, and a rock shaft rotatably mounted relatively to said table and having a connection with said pin to move said pin in any longitudinal position thereof, into and out of coöperative relation with the notches on said work-sheets.

8. The combination with a platen, of feed rolls for said platen, a finger-piece connected to spread said feed rolls away from said platen, one or more pins to coöperate with notches on work-sheets carried by said platen, so as to collate said work-sheets, a rock shaft for moving said pins into and out of coöperative relation with said notches, and a lever for operating said rock shaft superposed above said finger-piece, so as to simultaneously operate the same to spread said rolls, whereby, when said pins are in position to collate said work-sheets, said rolls will be spread from said platen to permit the placing of the work-sheets on said platen.

9. The combination with a platen, of one or more pins for engaging notches in work-sheets carried by said platen, so as to collate said work-sheets, and a rock shaft for adjusting said pins between operative and inoperative positions, said pins being T-formed, and said shaft having a slot extending longitudinally thereof having a T-shaped cross-section to receive said pins, so that said pins may be adjusted along said shaft to engage notches in work-sheets located at different longitudinal positions along said platen, so as to remain securely in position on said rock shaft.
